(57) **CLAIM**

The ornamental design for a non-invasive neurostimulation device, as shown and described.

DESCRIPTION

FIG. 1 is a front perspective view of a non-invasive neurostimulation device, showing our new design;
FIG. 2 is a right side view thereof;
FIG. 3 is a left side view thereof;
FIG. 4 is a top view thereof;
FIG. 5 is bottom view thereof;
FIG. 6 is a rear view thereof;
FIG. 7 is a front view thereof;
FIG. 8 is a front perspective view of a second embodiment of a non-invasive neurostimulation device, showing our new design;
FIG. 9 is a right side view thereof;
FIG. 10 is a left side view thereof;
FIG. 11 is a top view thereof;
FIG. 12 is bottom view thereof;
FIG. 13 is a rear view thereof;
FIG. 14 is a front view thereof;
FIG. 15 is a front perspective view of a third embodiment of a non-invasive neurostimulation device, showing our new design;
FIG. 16 is a right side view thereof;
FIG. 17 is a left side view thereof;
FIG. 18 is a top view thereof;
FIG. 19 is bottom view thereof;
FIG. 20 is a rear view thereof;
FIG. 21 is a front view thereof;
FIG. 22 is a front perspective view of a fourth embodiment of a non-invasive neurostimulation device, showing our new design;
FIG. 23 is a right side view thereof;
FIG. 24 is a left side view thereof;
FIG. 25 is a top view thereof;
FIG. 26 is bottom view thereof;
FIG. 27 is a rear view thereof, and,
FIG. 28 is a front view thereof.
The broken lines shown in the drawings represent unclaimed portions of the non-invasive neurostimulation device and form no part of the claimed design.
